US00D990546S

(12) **United States Design Patent** (10) Patent No.: **US D990,546 S**
(45) Date of Patent: **** Jun. 27, 2023**

(54) **CAMERA MOUNT**(71) Applicant: **GoPro, Inc.**, San Mateo, CA (US)(72) Inventors: **Ryan Harrison**, Walpole, NH (US);
Ross Thayer, San Jose, CA (US);
Arthur Kwun, Newark, CA (US);
Mark Costa, Menlo Park, CA (US)(73) Assignee: **GoPro, Inc.**, San Mateo, CA (US)(***) Term: **15 Years**(21) Appl. No.: **29/767,750**(22) Filed: **Jan. 25, 2021****Related U.S. Application Data**

(63) Continuation of application No. 29/726,067, filed on Feb. 28, 2020, now Pat. No. Des. 908,780, which is a continuation of application No. 29/699,948, filed on Jul. 30, 2019, now Pat. No. Des. 880,571, which is a continuation of application No. 29/665,322, filed on Oct. 2, 2018, now Pat. No. Des. 861,770, which is a continuation of application No. 29/610,474, filed on Jul. 12, 2017, now Pat. No. Des. 829,809, which is a continuation of application No. 29/561,955, filed on Apr. 21, 2016, now Pat. No. Des. 800,205, which is a continuation of application No. 29/525,956, filed on May 5, 2015, now Pat. No. Des. 757,842.

(57) CLAIM

The ornamental design for a camera mount, as shown and described.

DESCRIPTION

FIG. 1 is a front, top, and right side perspective view of a camera mount;

FIG. 2 is a front elevational view thereof;

FIG. 3 is a rear elevational view thereof;

FIG. 4 is a left side elevational view thereof;

FIG. 5 is a right side elevational view thereof; and,

FIG. 6 is a top plan view thereof.

The broken lines of equal length (i.e., dash-dash) in the drawings are included for the purpose of illustrating environmental structure and form no part of the claimed design.

1 Claim, 6 Drawing Sheets

FIG. 1

FIG. 2

FIG. 3

FIG. 4

FIG. 5

FIG. 6
